SOCK

Samuel Kay, Stamford, Conn., and Alcide O. Cormier,
Laconia, N. H.

Application August 6, 1956, Serial No. 42,514

Term of patent 14 years

(Cl. D47—7)

The figure of our new design shows a perspective view showing the outside face of one sock of a pair of socks showing a single lace interlaced through eyelets in the said outside face, the inside or opposite face being merely knitted.

We claim:

The ornamental design for a sock, substantially as shown and described.
